[57] CLAIM

The ornamental design for a portfolio, substantially as shown and described.

DESCRIPTION

FIG. 1 is a perspective view of a portfolio showing my new design;

FIG. 2 is a rear elevational view;

FIG. 3 is a bottom plan view;

FIG. 4 is a right end elevational view;

FIG. 5 is a perspective view, similar to FIG. 1, but with the cover flap raised;

FIG. 6 is a rear elevational view, similar to FIG. 2, but with the cover flap raised; and

FIG. 7 is a fragmentary perspective view of the top of the portfolio with the handles retracted.
